(57) **CLAIM**

The ornamental design for the adjustable labeling apparatus for bottles and jars, as shown and described.

DESCRIPTION

FIG. 1 is a front perspective view of the adjustable labeling apparatus for bottles and jars of present invention;

FIG. 2 is a front elevation view thereof;

FIG. 3 is a rear elevation view thereof, wherein several components are in alternate positions;

FIG. 4 is a right end view thereof;

FIG. 5 is left end view thereof; and,

FIG. 6 is a top view of the present invention.

The broken line showing of the bottle is provided for purposes of environment and forms no part of the claimed design. The areas of the adjustable labeling apparatus for bottles and jars that is shown in broken line form are not considered part of the claimed design.

1 Claim, 5 Drawing Sheets
